UNITED STATES PATENT OFFICE

HARLEY J. EARL, RALPH W. PEW, AND JOHN J. TJAARDA, OF DETROIT, MICHIGAN,
ASSIGNORS TO GENERAL MOTORS CORPORATION, OF DETROIT, MICHIGAN, A COR-
PORATION OF DELAWARE

DESIGN FOR A HUB FOR STEERING WHEEL

Application filed July 8, 1929. Serial No. 31,972. Term of patent 14 years.

To all whom it may concern:

Be it known that we, HARLEY J. EARL, RALPH W. PEW, and JOHN J. TJAARDA, citizen of the United States, resident of Detroit, county of Wayne, and State of Michigan, citizen of the United States, resident of Detroit, county of Wayne, and State of Michigan, and citizen of Holland, resident of Detroit, county of Wayne, and State of Michigan, respectively, have invented a new, original, and ornamental Design for a Hub for Steering Wheel, of which the following is a

specification, reference being made to the accompanying drawing forming a part thereof.

Figure 1 is a perspective view looking from the bottom of the novel hub.

Figure 2 is a side view of the hub.

We claim:

The ornamental design for a hub for steering wheel, substantially as shown.

HARLEY J. EARL.
R. W. PEW.
J. J. TJAARDA.
